UNITED STATES PATENT OFFICE.

WILLIAM RILEY, OF HENRY, SOUTH DAKOTA.

WRENCH.

1,243,876.

Specification of Letters Patent. Patented Oct. 23, 1917.

Application filed February 14, 1917. Serial No. 148,501.

To all whom it may concern:

Be it known that I, WILLIAM RILEY, a citizen of the United States, residing at Henry, in the county of Codington and State of South Dakota, have invented certain new and useful Improvements in Wrenches; and I hereby declare that the following is a full, clear, and exact description thereof, reference being had to the accompanying drawings, which form part of this specification.

This invention is a novel improvement in pipe and rod wrenches and the object of the invention is to provide a simple, efficient, quick acting, powerful gripping wrench which may be manipulated by one hand; which will not slip on the pipe or rod nor crush the pipe and which will quickly engage a pipe or rod of any size, within the capacity of the wrench, and which is capable of engaging a considerable variety of sizes of rods and pipes from the minimum to the maximum capacity of the wrench.

The invention will be fully understood from the accompanying drawings and the following description, and the essential features of the wrench are summarized in the claims.

In said drawings:

Figure 1 is a side view of the wrench with the parts in normal position.

Fig. 2 is an enlarged view thereof showing it engaged with a pipe.

Fig. 3 is a detail.

The wrench comprises a handle 1, main jaw 2, minor jaw 3, swinging links 4 pivotally connecting jaws 2 and 3, swinging links 5 pivotally connecting jaw 3 with the handle, and a spring 6 connected with the handle and the main jaw.

As shown the main jaw 2 is approximately scythe or hook shaped, and is connected at one end by a pivot bolt or rivet 1^a to the adjacent end of the handle 1. The concave or inner edge of the jaw 2 is toothed or serrated as at 2^a, and its point 2^b lies almost at right angles to the main body of the jaw owing to the curvature thereof.

The minor jaw 3 is pivoted on a bolt or rivet 3^c connected with the ends of swinging links 4, the other ends of which links are pivoted by a bolt or rivet 4^a to the jaw 2 near its pivot 4^a so that the minor jaw 3 can have both a rocking motion on its pivot 3^c relative to the jaw 2 and also have a swinging motion on the pivot 4^a relative

to jaw 2. The jaw 3 also has a curved portion 3^a which is toothed or serrated on its convex face opposite the serrations 2^a of the main jaw. The minor jaw 3 has a shank 60 3^b extending in rear of pivot 3^c and connected by a pin or rivet 3^d to the ends of links 5 the other ends of which links are pivoted by a bolt or pin 5^a to the handle 1, adjacent and in rear of the pivot 1^a. 65

The minor jaw 3 is provided with a fulcrum or abutment 3^e which is adapted to engage a corresponding recess or shoulder 2^e in the jaw 2 and when so engaged this abutment transmits direct pressure from the 70 point of engagement of the jaw 3 with the object to the point of engagement of the abutment with the jaw 2 and largely relieves the links 4 and 5 from strain during the operation of the wrench. 75

The construction is such that if the jaw 2 is swung relatively to handle 1 so as to move the major portion of the jaw toward a position in line with handle 1, the jaws will open; but if jaw 2 is turned at an angle 80 to the handle 1 the jaws will tend to close, and engage a rod or pipe P as indicated in Fig. 2; and if the parts are in the position shown in Fig. 2 the greater the downward pressure exerted on handle 1 the 85 greater will be the bite of the jaw upon the pipe or rod.

A spring 6, preferably a helical spring, is connected at one end to the handle 1 and its other end is connected to a bail 6^a, the outer 90 ends of which are shown as pivotally connected to the jaw 2 by a pin 6^b, the spring and bail forming a yielding connection between the handle and the main jaw 2; and the spring normally tending to swing the jaws to the position shown in Fig. 1, which is their normal idle position. The spring 6 may be inclosed in a casing 6^c of any desired construction, attached to or formed on the handle 1, to protect it from injury. 95 100

Operation.

The wrench may be engaged with a pipe or rod by simply hooking the point 2^b of the main jaw over or against the rod or pipe and then pulling lineally on the handle in a direction tending to move the jaw 2 into line with the handle, which movement will cause the jaws to open until the wrench can be slipped into engagement with the rod or pipe as indicated in Fig. 2. The tension of the spring 6 will cause the jaws to bite the 110

rod or pipe as soon as the lineal pull ceases. When engaged with an object a pull on the handle in the direction indicated by the arrow in Fig. 2 will cause the jaws to firmly 5 bite the rod or pipe and compel the latter to turn therewith.

A very powerful grip is obtained by reason of the thrust of the links 5 against the shank of the jaw 3 tending to oscillate it on its pivot 3^e and fulcrum 3^e and swing jaw 3 10 toward jaw 2.

A backward movement of the handle 1 or a lineal pull thereon will cause the jaws 15 to open and enable the wrench to be readily disengaged from the rod or pipe.

In using the wrench a large portion of the thrust exerted by the jaw 3 on the rod is transmitted direct from the abutment 3^e to the shoulder 2^e of the jaw 2 and consequently 20 the pivots of the links are relieved of a great deal of strain. The wrenches are powerful, simple, easily applied, and may be made of various sizes according to the sizes of pipes and rods with which they are to be used.

25 What I claim is:

1. In a wrench the combination of a handle; a main jaw pivotally connected with the handle; a minor jaw opposite the main jaw; links pivotally connecting the minor jaw with the main jaw; links pivotally connecting the shank of the minor jaw with the handle; and a spring connected with the handle and main jaw, substantially as described.

2. In a wrench the combination of a han-

dle, a main jaw pivotally connected with 35 the handle and having a shoulder near its pivot, a minor jaw pivotally connected with the main jaw, links pivotally connecting the shank of the minor jaw and the handle; said minor jaw having an abutment adapted to 40 engage the shoulder of the main jaw.

3. In a wrench the combination of a handle, a main jaw pivotally connected with the handle, and a minor jaw having a shoulder near its pivot, a minor jaw pivotally connected with the main jaw, links pivotally connecting the shank of the minor jaw and the handle, said minor jaw having an abutment 45 adapted to engage the shoulder of the main jaw; and a spring connected with the handle and the main jaw, substantially as described.

4. In a wrench the combination of a handle, a main jaw pivotally connected with the handle, a minor jaw opposite the main 55 jaw, links pivotally connected with the minor jaw and with the main jaw, links pivotally connected with the shank of the minor jaw and the handle, said main jaw having a shoulder near its pivot, and said minor jaw 60 having an abutment or projection adapted to engage the shoulder of the main jaw; and a spring connected with the handle and the main jaw, substantially as described.

In testimony that I claim the foregoing as 65 my own, I affix my signature.

WILLIAM RILEY.
